Patented Aug. 30, 1927.

1,641,111

UNITED STATES PATENT OFFICE.

JOHN FREDERICK BLACKMON, OF LAURENS, SOUTH CAROLINA.

LOOM DOBBY.

Application filed December 6, 1926. Serial No. 152,863.

My invention relates to loom dobby constructions, more particularly to the pattern mechanism of dobby's, of the type wherein in upper and lower pattern cylinders are employed. The present invention is an improvement over the present type of such mechanisms as illustrated in the United States patent to H. Hattoy, No. 1,487,654 issued March 18, 1924.

In the operation of such looms as are typified by the Hattoy patent, the weaving of end border designs is accomplished by upper pattern cylinder mechanism, at regularly determined intervals. The side edge borders are formed through the medium of the main, or lower pattern cylinder mechanism, and suitable means on the loom holds the lower pattern cylinder inoperative while the upper or auxiliary cylinder is in operation. Operating connection is maintained between the upper and lower dobby fingers by means of links connected between the front ends of the fingers, and the pattern chain of the upper pattern cylinder is confined within the dobby head behind the wall of connecting links. Due to the necessarily limited space, the upper pattern chain must be short, and as a consequence only a limited design can be utilized for end borders.

It is an object of my invention to provide a structural arrangement of dobby head mechanism constituting a means whereby an upper pattern chain may be employed, the length of which is only determined by the power of the loom to pull it, thereby permitting the utilization of a practically unlimited field of more complicated end border design weaving than is now possible.

Another object is the provision in a dobby head mechanism of this general type, of means operatively connecting the upper and lower dobby fingers in such manner as to leave the front of the dobby frame open to accommodate passage therethrough of a relatively lengthy upper pattern chain.

A further object is the provision of a novel operating connection means between sets of upper and lower dobby fingers.

With these and such other objects in view as will be apparent from the description, the invention resides in the novel construction, combination and arrangement of parts hereinafter described and claimed, and illustrated in the accompanying drawings, wherein is shown one practical embodiment of the principles of the invention.

Figure 1 is substantially a side elevation of a dobby frame illustrating the connection between upper and lower sets of the dobby fingers. 60

Figure 2 is an end elevation of the dobby fingers and their connecting elements.

Figure 3 is a perspective view of an applied connector between a pair of vertically aligned dobby fingers. 65

Figure 4 is a perspective of the connector element shown in Figure 3.

Figure 5 is a perspective of another of the connector elements employed.

As shown in Figure 1, the reference character 10 indicates generally the frame of a dobby head of the type shown in the above referred to Hattoy patent. The frame carries a main lower pattern drum or cylinder 11 provided with the conventional pattern chain 12 in the usual manner. A shaft 13 disposed transversely across the dobby head forms the pivot for the lower dobby fingers. These fingers are arranged in sets of pairs, side by side across the head, but for convenience of illustration only the component members of one pair are illustrated. One finger 14 is substantially of the conventional lower dobby finger configuration, except that its upturned rear end, upon which rests a jack hook 15 is formed with a substantially vertical elongated slot 16. The other finger 17 of the pair has its rear end formed in a rearwardly extending lug 18 provided with a flat top edge in substantially the horizontal plane of the axis of the pivot shaft 13. 70 75 80 85 90

The auxiliary or upper pattern cylinder 19 is arranged in the dobby head above the lower cylinder 11, and is provided in the usual manner with a pattern chain 20, which chain 20 differs from the lower pattern chain in that it is passed through the open front of the dobby head and is of considerable length, being supported by means (not shown) externally of the dobby head. 95 100

The upper sets of dobby fingers are pivoted on a shaft 21 arranged above the shaft 13, and the sets of these upper fingers are arranged in pairs similar to and vertically aligned above the sets of lower fingers. Each of the upper dobby fingers, one of which is shown as 22, and the other as 23, are provided with rear end extensions. The finger 22 is arranged in vertical alignment 105 over the lower finger 14 and has its rear end extension 24 turned downwardly and 110

perforated for a purpose to be described. The finger 23 arranged over the lower finger 17, has its rear end extension in the form of a lug 25 identical with the lug 18 of the lower finger over which it is arranged.

As best shown in Figures 3 and 4 the element operatively connecting the rear ends of the upper and lower fingers 22 and 14, comprises a rod 26 having a straight shank and being bent at a right angle at each end to form securing pins 27 and 28, the upper of which, 27, is adapted for engagement in the perforation of the rear end extension 24 of the upper finger 22, and the lower of which, 28, is adapted to be received in the slot 16 with which the rear extension of the lower dobby finger 14 is provided. Intermediate its ends the rod 26 has rigidly secured thereto, by welding or other suitable means, a wire 29 paralleling the rod 26 through the major portion of its length. The lower end of the wire 29 is bent outwardly and down to form a guard finger 30 adapted to engage over the side of the rear extension of the lower finger 14 opposite to the side from which the pin 28 is inserted in the slot 16. At its upper end the wire 29 is bent upon itself to form a guard 31 adapted for engagement over the side of the upper finger extension 24 opposite to that from which the pin 27 is inserted in the perforation with which the extension is provided. By the provision of the guards 30 and 31, the connecting rod 26 is securely retained in position when applied, and as the wire 29 is connected to the rod at an intermediate point, the ends of the wire have sufficient flexibility to be separated from the ends of the rod, permitting application thereof in service position. The inherent tension of the wire 29 will restore the guards to normal position.

The upper and lower dobby fingers 23 and 17 respectively, are connected by a push rod 32 having a straight shank, the lower end of which is seated on the flat top edge of the lower dobby finger lug 18. At its upper end the rod 32 is formed in an elongated loop 33 passed over the rear lug 25 of the upper dobby finger 23. The loop 33 is extended upwardly sufficiently so that its top forms a seat for an upper jack hook 34 of the loom.

In the operation of the loom while the design is weaved in the main body portion of the work, the loom mechanism holds the upper pattern cylinder inoperative while the lower pattern cylinder is operated to move its pattern chain 12 beneath the sets of the lower fingers 14 and 17. When a finger 14 is rocked on its pivot the rear end supporting a jack hook 15 is depressed, permitting the jack hook to engage the usual knife (not shown). The length of the connecting rod 26 is such that normally the pin 28 rests on the bottom of the slot 16, and consequently on depression of the rear end of the finger

14, the pin 28 rides free in the slot and there is no actuation of the corresponding upper dobby finger 22. Likewise, movement of the lower dobby finger 17 depresses the lug 18, and by virtue of the elongated loop 33 at the upper end of the rod 32, no corresponding actuation of the upper dobby finger 23 is brought about.

However in the design weaving for the end borders it is necessary that the corresponding sets of upper and lower dobby fingers move in unison. When the border point is reached, the loom mechanism renders the lower cylinder 11 inoperative and throws the upper cylinder 19 into operation. As under the action of the pattern chain 20 the upper dobby finger 22 is rocked on its pivot, the rear extension 24 will be depressed and by virtue of the fact that the pin 28 of the connecting rod 26 rests on the bottom of slot 16, the corresponding lower dobby finger 14 will also be rocked on its pivot. Likewise, as in normal inoperative position, the rear lug 25 of the upper dobby finger 23 rests on the bottom of the loop 33, when the lug is depressed through rocking of the finger, the lower end of the push rod 32 will cause a corresponding rocking of the lower dobby finger 17 on its pivot, and the jack hook 34 will be lowered for engagement with the knife (not shown).

I claim:—

1. In a loom dobby having a main pattern cylinder and an auxiliary pattern cylinder with dobby fingers associated with each, members operatively connecting said dobby fingers at points between said cylinders and the dobby frame adjacent the shedding levers of the loom.

2. In a loom dobby having upper and lower pattern cylinders and sets of dobby fingers cooperating with the respective cylinders, rods connecting the inner ends of vertically aligned pairs of said dobby fingers.

3. In a loom dobby having upper and lower pattern cylinders and sets of dobby fingers cooperating with the respective cylinders, extensions formed on the inner ends of said fingers, and rods operatively connecting vertically aligned pairs of said extensions.

4. In a loom dobby having upper and lower pattern cylinders, a set of dobby fingers disposed for cooperation with each of said cylinders, means pivotally mounting said fingers at a point in rear of said cylinders and intermediate the ends of the fingers, and rods operatively connecting the ends of said fingers in vertically aligned pairs, said rods being disposed in rear of the pivotal point of the fingers.

5. In a loom dobby, a lower pattern cylinder, an upper pattern cylinder, lower dobby fingers and upper dobby fingers cooperating

with said cylinders respectively, and means disposed internally of the dobby behind said cylinders for actuating said lower fingers from corresponding upper fingers.

5. 6. In a loom dobby, a pattern cylinder, and a pattern chain on said cylinder supported for passage through the front of the dobby.

7. In a loom dobby, an upper pattern cylinder, a lower pattern cylinder, dobby fingers associated with said upper cylinder,

15
dobby fingers associated with said lower cylinder, rear end extensions formed on said dobby fingers, and operating rods connecting vertically aligned pairs of said extensions, said rods being arranged for depressing the extensions of said lower fingers upon depression of the extensions of said upper fingers.

In testimony whereof I affix my signature. 20

JOHN FREDERICK BLACKMON.
